LID FOR MULTIPLE BOXES AND METHOD
OF APPLYING THE SAME

Walter Hale Paxton, also known as Hale Paxton, deceased, late of Riverside, Calif., by Geraldine Paxton and H. S. Nicks, executors, Riverside, Calif., assignors to Food Machinery Corporation, San Jose, Calif., a corporation of Delaware

Application April 29, 1940, Serial No. 332,320

5 Claims. (Cl. 1—10)

This invention relates to the packaging art and more particularly to the closing of multiple containers.

For the past generation, at least, the trend in merchandising has been toward doing away with the retailer's handling goods in bulk and the assumption by the processor of the function of packaging the goods in units suitable for meeting the needs of individual purchasers for home use. This tendency has not been so marked in the merchandising of perishables such as fresh fruits. One of the reasons for this has been the lack of a suitable container in which fresh fruit can be packaged and transported economically and at the same time provide individual packages of a size small enough to pass unbroken through retail channels to the ultimate consumer. It is with the purpose of solving this problem that a multiple box was developed by Walter Hale Paxton, said box having a multiplicity of individual containers, all of which are integrally united as a multiple package.

It having been the custom for many decades in the fruit shipping industry to pack fruit in boxes so that the fruit extends above the upper end of the box and causes an arch in the cover when this is applied, it was found advisable, if not necessary, for each of the individual containers in a multiple box aforesaid to be provided with an arched cover to accommodate an over-filled pack in each individual container, and that this be done in such a way that when the multiple box is disassembled at the retailer's into its constituent units, each of the latter would retain an arched cover applied thereto in much the same manner as arched covers have universally been applied to large size fresh fruit packing crates.

It is accordingly a broad object of this invention to provide a novel method of lidding a multiple box and a specific object to provide such a method by which all the units in the box will be supplied with a separate, individual, arched cover accommodating an over-pack in said unit.

Each multiple box is handled in the packing of fruit as a unit and is shipped as a unit or after being further assembled into larger compound multiple boxes. A distinct problem is thus presented in the lidding of the individual unit containers. It is of course especially desirable that the lidding of each of said multiple boxes be accomplished as expeditiously as possible.

Accordingly, it is another object of this invention to provide a method of simultaneously lidding the individual packed box units of a multiple

box so that when the multiple box is disassembled each unit will have a separate individual lid.

The manner of accomplishing the foregoing objects, as well as further objects and advantages, will be made manifest in the following description taken in connection with the accompanying drawing, in which:

Fig. 1 is a perspective view of a preferred form of the lid of the invention.

Fig. 2 is a diagrammatical front elevational view of a preferred form of lidding machine suitable for carrying out the lidding operation of the process of this invention.

Fig. 3 is a fragmentary view of the machine shown in Fig. 2 and illustrating the completion of the cover pressing step of the process of this invention.

Fig. 4 is a perspective view of a multiple box after this has been lidded in accordance with the method of this invention.

Fig. 5 is a perspective view of a clasp suitable for use in making said box.

The lid and process of this invention are adapted to be used with various types of multiple boxes.

For illustrative purposes, a multiple box 10 is shown in the drawing, which was invented by Walter Hale Paxton. This box is made up of two sections 11 which are joined together by placing these sections alongside each other and uniting the abutting ends of these as by clasps 12. Each of the box sections 11 includes ends 13, center partitions 14, these ends and partitions having secured thereto bottom slats 15, inner side slats 16 and outer side slats 17. Two box units 18 are thus provided in each section 11. The outer side slats 17 are provided with scorings 19 which are formed along the line on which the units 18 come together. Prior to the assembly of the sections 11, the inner side slats 16 are severed along lines disposed between the units 18 and at some time prior to shipment of the box 10 the bottom slats 15 are also severed along the line of meeting of the units 18. Thus, when the sections 11 are separated by removing the clasps 12 for the purpose of disassembling the box 10, it is possible, by swinging the units 18 relative to each other about the lines of the scorings 19, to fracture the unsevered portions of the slats 17 and thus completely separate the units 18.

The problem here faced is to provide an expeditious way of lidding all of the units 18 of the box 10 after these have been over-packed with fresh fruit, so that the box 10 may be thus disassembled, and so that when it is thus disassem-

bled each of the units 18 will be provided with a suitable lid.

This problem has been solved by the provision of a unitary lid 20 which is made up preferably of a plurality of straight-grained thin wooden slats 21, there being four of these slats in the lid 20 so as to render the latter suitable for lidding the box 10. These slats are bound together to produce the unitary lid 20 by nailing or stapling these slats to end cleats 22 and a central cleat 23. The latter cleat is preferably twice as wide as the end cleats 22 and is weakened along its central axis by a saw cut 24 which extends vertically entirely through said cleat 23 but stops short of the ends of said cleat. The slats 21 in the lid 20 are preferably entirely severed, as by saw cuts 25, along a transverse middle line of the lid 20 in the same plane of the saw cut 24. The cleats 22 and 23 are also preferably weakened along the longitudinal axis of the lid 20 by scorings 26 and 27.

The lidding of the box 10 with the lid 20, in carrying out the method of this invention, is performed as follows:

The box 10 is delivered onto a nailing table 30 of a lidding machine 31 just after all of the units 18 of the box have been packed with fruit so as to produce an over-filled or crown pack 32 in each of these units. The lidder 31 is provided with a suitable elevator 33 for reciprocating the table 30 vertically and has an overhead frame 34 which carries end nailing devices 35 and middle nailing devices 36. Supported between these nailing devices are crown sheet plates 37. Provided on the nailing devices 35 are lid supports 38.

Just before beginning the lidding operation of the box 10, one of the lids 20 is placed in the lidding machine 31 with the ends of this lid resting on the supports 38. The elevator 33 is then operated to raise the table 30 and the box 10 resting thereon until the ends of the lid 20 are compressed between the ends of the box 10 and the nailing devices 35, and the middle of the lid is compressed between the partitions 14 of the box 10 and the nailing devices 36, so as to arch the slats 21 of the cover 20 upwardly into contact with the crown sheets 37. The nailing devices 35 and 36 are now operated either by separate mechanism or by continuing the upward movement of the table 30 in a manner well-known in the art, so as to drive nails downwardly through the lid 20 into the ends 13 and partitions 14 of the box 10. The table 30 is then lowered and the box 10 removed therefrom, this now appearing as shown in Fig. 4.

While the saw cuts 25 preferably completely sever the slats 21 of the lid 20 along their central transverse axes, the saw cut 24 does not completely sever the central cleat 23 but leaves end portions of this cleat unbroken and these end portions serve, during the handling of the lid in the lidding operation, to connect the opposite end portions of the lid. The cleat 23 is so attached to the slats along its opposite side edges that when the box 10 is lidded the downward inclination of the portions of the lid 20 on opposite sides of the central transverse axis thereof tends to split the ends of the cleat 23 along said axis and bends opposite side portions of said cleat in conformity with the adjacent portions of the slats 21 as shown in Figs. 3 and 4. Thus, when the box 10 is lidded, the lid 20 is practically completely divided along its central transverse axis into two halves and the central cleat is divided along

its axis to provide separate inner end cleats for said lid halves.

The box 10 is now ready for being placed in the car for shipment, or it may be placed bottom-to-bottom with another similar box and bound together therewith by clasps so as to make a single box for shipping purposes. Upon being received at their final point of distribution—that is, at the retailer's—the boxes 10, after being freed from any clasps holding them together in pairs, are disassembled.

The first step of this disassembly is to remove the clasps 12. The sections 11 are now rotated relative to each other about the line of the scorings 26 and 27, fracturing those portions of the slats 22 and 23 remaining unbroken along this line until the complete separation of the two sections 11 is effected. The units 18 of each of these sections are now free to be rotated about the lines of the scorings 19, this rotation fracturing those portions of the slats 17 unbroken along this line, and resulting in the separation of these units being completed. Each of these separate units, when thus disassembled, has an arched lid of its own which constitutes one-fourth of the lid 20.

It is thus seen that this invention provides a novel lid for lidding a multiple box and a method of applying the same by which said lid may be expeditiously applied in a manner to simultaneously lid all of the box units for said box whereby, when said box is disassembled into its constituent units at its ultimate point of distribution, each of said units is provided with a separate arched lid.

What is claimed is:

1. The method of lidding a multiple box having a multiplicity of individual box units arranged on opposite sides of a given dividing line, each of said units being over-filled with perishable farm produce, which comprises: applying to said box a unitary lid adequate, when divided, to supply individual covers to said box units and weakened along the aforesaid line; pressing end portions of said lid and portions adjacent said line downwardly into contact with said box to arch said lid between said portions upwardly over said farm produce; and fastening to said box the lid portions contacting the same.

2. The method of lidding a multiple box having a plurality of individual box units each having its own opposite end walls and assembled together in such a manner as to permit their being readily disassembled when so desired, said method comprising: applying to said box a unitary lid adequate to cover all of said units and weakened along lines corresponding to the lines on which said units are joined to form said multiple box, said weakening causing said lid to fracture cleaning when bent along said lines; pressing portions of said lid into contact with opposite end walls of each of said units; and securing said lid to each of said unit end walls.

3. The method of lidding a multiple box having a plurality of individual box units each having its own opposite end walls and assembled together in such a manner as to permit their being readily disassembled when so desired, said method comprising: applying to said box a unitary lid adequate to cover all of said units and weakened along lines corresponding to the lines on which said units are joined to form said multiple box, said weakening causing said lid to fracture cleanly when bent along said lines; pressing portions of said lid into contact with opposite end

70 walls of each of said units; and securing said lid to each of said unit end walls.

walls of each of said units; and simultaneously securing said lid to each of said unit end walls.

4. The method of lidding a multiple box having two rows of individual box units, there being a plurality of said units in each of said rows, the units in said box being assembled together in such a manner as to permit their being readily disassembled when so desired, said method comprising: providing a unitary lid adequate to cover all of said units and weakened along a line corresponding to the line on which said rows are joined to form said multiple box; said lid also being weakened along lines corresponding to the lines on which said units are joined in each of said rows; applying said lid to said box; and securing said lid to end portions of each of said units.

5. A unitary lid adapted for use in lidding a

multiple box having two sections, each of which sections contains two individual box units, said lid comprising: slat means; end cleats for connecting said slat means and adapted to extend along the ends of said sections; a central cleat means joining said slat means along a line corresponding to the dividing plane between said units in each of said sections, all of said cleat means being weakened along a line corresponding to the plane of meeting of said sections, said intermediate cleat means being weakened along the line of division between said units while said slat means are completely severed along said last mentioned line.
